(57) **CLAIM**

The ornamental design for a center console for an automobile, as shown and described.

DESCRIPTION

FIG. 1 is a front, top, right side perspective view of a center console for an automobile, showing my new design; FIG. 2 is a rear, top, right side perspective view thereof; FIG. 3 is a front elevational view thereof; FIG. 4 is a rear elevational view thereof; FIG. 5 is a top plan view thereof; FIG. 6 is a bottom plan view thereof; FIG. 7 is a right side elevational view thereof; and, FIG. 8 is a left side elevational view thereof.

The broken lines depict a boundary around the de-emphasized elements, which illustrate portions of the center console for an automobile which form no part of the claimed design.
